UNITED STATES PATENT OFFICE.

HERMAN L. SEEKAMP, OF GILLESPIE, ILLINOIS.

MINING-MACHINE-CHAIN LUBRICATOR.

Application filed April 20, 1925. Serial No. 24,369.

My invention relates to improvements in apparatus for oiling the cutter chains for chain mining machines.

One of the objects of my invention is to provide an apparatus which may be applied to the present commercial form of chain mining machine and which will deliver oil in proper amount to the cutter chain during the operation of the machine.

For the purpose of disclosing my invention I have illustrated one embodiment thereof in the accompanying drawings in which—

Fig. 1 is a fragmentary perspective view of so much of a mining chain cutter as is necessary for the purpose of illustrating the application of my invention;

Fig. 2 is a transverse sectional view of the oiler;

Fig. 3 is a longitudinal sectional view of the same and

Fig. 4 is a detail sectional view of the pump piston.

In the embodiment illustrated my invention is shown as used in connection with the usual commercial type of chain mining machine having a relatively stationary frame provided with side bars such as 1 and a relatively movable frame having chain cutter guides 2 and provided at its rear end with a framework such as 3 for the driving mechanism for the chain cutter 4 operating in the guides. As is usual in this type of machine the movable framework is projected forwardly against the breast to be cut and moves on the stationary frame 1. After the movable frame has been projected to the limit of its movement it is retracted and after the material has been cleaned from in front of the cutter the relatively stationary frame is moved forward again and the cutting operation again takes place.

In the embodiment illustrated the lubricant container 5 comprises a rectangular box having a lateral extension 6 which is shorter than the height of the box 5. By this construction the container may be conveniently mounted on the movable frame 1 in a position where it takes up the minimum of space and where it can most conveniently deliver the lubricant to the cutter chain. The overhang or shallow portion 6 overhangs the top of the side guide 1 while the deeper portion 5 of the container extends downwardly along the inner face of the side rail. This box is provided on its

rear end with an ear 7 by which it may be bolted to a part of the moving frame 3. The shallow container portion 6 comprises in itself a container into which the oil or lubricant is adapted to be poured through an opening 8 in the top 9 of the container which opening is normally closed by a suitable cap 10, and the container 6 feeds into the portion 5 through an opening 11 in the side wall 12, which opening is covered by a screen 13 for straining the lubricant before it passes into the container portion 5.

Within the container portion 5 I mount a pump comprising a casting 14 having a cylinder 15 formed therein, the bottom of which communicates through a port 17 with the container and during the delivery stroke of the piston this port is closed by a ball check valve 18. The bottom of the cylinder 15 communicates through ports 19 and 20 with a chamber 21 connected by a suitable hose 22 with the delivery pipe 23 mounted on the exterior of the container. Arranged in the bottom of the chamber 21 is a ball check valve 24 which checks the flow of the fluid in the chamber during the suction stroke of the piston. Operating in the cylinder 15 is a hollow piston 24 having at its lower end a series of annular grooves 25. At the center or middle of these grooves the cylinder is provided with a series of radial ports or openings 26 through which the interior of the cylinder communicates with the exterior of the cylinder. Due to the fact that the piston is submerged in the oil most of the time, the oil will seep in through the openings 26 to the interior of the piston and during the reciprocating movement of the piston this oil flowing out through the openings forms an effective oil seal between the piston and the walls of the cylinder.

The cylinder is reciprocated by an oscillating shaft 27 having a crank arm 28 connected with the piston 25 by a link 29. A coiled spring 30 surrounding the shaft 27 and having one end connected to the crank arm 28 and the opposite end stationarily connected to the partition or wall 12 tends to maintain the piston 25 in its raised or retracted position. The outer end of the shaft 27 is provided with a crank arm 31 adapted, as the movable frame moves forwardly, to engage a stop 32 on the stationary frame and rotate the shaft 27 to move the piston 25 downwardly on its delivery

stroke, this arm 31 being provided with an extension 33 pivoted at 34 to the arm in such a manner that when it engages the stop 32 when moving in one direction it will rotate the shaft 27, but when it engages the stop when moving in the opposite direction, will move on its pivot 34 without affecting the shaft. By the provision of an adjustable stop 35 the distance the piston 25 moves upwardly under the influence of the coiled spring 30 may be varied to thereby vary the stroke of the piston in accordance with the amount of oil delivery required. The delivery pipe 23 terminates in a forked nozzle, one leg 36 of which delivers oil to the top of the cutter chain while the other leg 37 directs the oil to a point between the cutter chain and the cutter chain guide.

I claim as my invention:

- 20 1. A chain oiler for mining machine cutters comprising an oil receptacle having an oil sump, an oil pump mounted in said sump and including a reciprocating piston, an oscillating shaft having a crank arm connected to said reciprocating piston, a spring for retracting said crank arm to move the piston on its suction stroke and means exterior of the receptacle connected to said shaft, engaged by a moving part of the machine for operating the piston on its forcing stroke.

2. An oiler for the cutting chain of a mining machine comprising an oil receptacle having an oil sump, a pump mounted in said sump, means exterior of the receptacle arranged to be engaged by a moving part of a mining machine for operating said pump, a forked nozzle mounted upon the exterior of the receptacle and arranged to deliver oil to the chain cutter and the conduit extending between said nozzle and said oil pump.

3. An oiler for the cutting chain of a mining machine, comprising an oil receptacle having an oil sump, a pump mounted in said sump comprising a cylinder having an intake opening at its bottom, a check valve for closing said opening in one direction, said cylinder delivering into an oil conduit and a check valve in said conduit for closing the same in one direction, a delivery nozzle on the exterior of said casing connecting with said conduit and arranged to deliver oil to the cutting chain and means on the exterior of the casing arranged to be engaged by the moving part of a mining machine for operating said pump.

In witness whereof, I, HERMAN L. SEEKAMP, have hereunto set my hand at Gillespie, Illinois.

HERMAN L. SEEKAMP.
